UNITED STATES PATENT OFFICE

ARTHUR E. DAVENPORT, OF MAYWOOD, ILLINOIS

OIL-PUMP BATTERY UNIT

Application filed July 23, 1928. Serial No. 294,910.

This invention is directed to a unit cabinet container for the reception of a plurality of oil tanks and connected pumps to group the tanks and pumps for display purposes and for the convenient delivery of the different grades or kinds of oils in the tanks.

Cabinets of this character are designed to receive and house, as a unit structure, several, usually four or more, tanks with their connected pumps, the respective pumps being designed to contain different grades of the same oil or different oils. The cabinet is usually positioned on the "island" platforms of filling stations and make for convenience and expedition in service, in that a customer may drive his car alongside the cabinet, select the desired oil, and be served directly from the cabinet without loss of time and with reasonable certainty of the character of the product.

An object of the present invention is the provision of a cabinet in which the tanks and carried pumps may be independently assembled or removed, together with means for securing the assembled tanks as a unit with the cabinet, the complete independence of the tanks permitting the removal or replacement of any one without disturbing the remaining tanks.

A further object is the provision of a cabinet in which the tanks form the lower front and rear walls, the area above the tanks being provided with movable closures, which when displaced open the upper area of the cabinet in which the pumps are located for full display from both front and rear of the cabinet, permitting use from front or rear as convenient.

A further object is to provide closures for the open area of the cabinet which slide downwardly to expose the pumps under a dash-pot retarder, permitting the closures to be merely released from the closed positions without further attention.

A further object is the provision of means whereby the respective tanks are secured in relatively fixed relation in the cabinet, the securing means serving at the same time to prevent upward movement of any of the tanks.

A further object is the provision of a removable hood provided with concealed illuminating means, said hood serving as a reflector to flood light the pumps and having means to interlock with the closures when the latter are raised, a single key-controlled lock governing all locking means.

The invention is illustrated in the accompanying drawings, wherein

Figure 1 is a perspective view of the improved battery unit, the doors being shown in raised or closed position.

Fig. 2 is a perspective view of the cabinet with parts removed.

Fig. 3 is an inverted view of the hood.

Fig. 4 is a sectional detail of the retarding provisions for the closures.

Fig. 5 is a detail of the locking means.

The battery unit comprises a skeleton frame, including side walls 1 and 2, connected near their lower ends by end bars 3 and side bars 4, and at points intermediate their lengths by side bars 7. The side bars 7 and 4 are connected by upright frame bars 5, which are continued beyond bars 4 to provide feet 6. The upper edges of the bars 7 are inwardly flanged or curved to constitute a tie or stay for the tanks, as will later appear. The bars 3 and 4 have inwardly extending flanges 10 and 9, respectively, to form a support for the tanks, a supporting strut 11 connected to the bars 3 at their mid-lengths, providing addition tank support.

The head room above the cross bars 7 is for access to the tanks and pumps, and is of course open during use of the unit, and otherwise is closed. For this purpose sliding doors 12 are provided. In order fully to expose the surfaces of the closure at all times, thus rendering them useful for advertising purposes, the doors are arranged for vertical sliding movement, moving downwardly to open the head room and upwardly to close the same.

It is a merit of the invention that the simple release of the duplicate sign panels or doors permits them to move under their own weight to open or pump exposing position. This is accomplished in a relatively slow and orderly fashion through the instrumentality

of retarding elements operating on the dash-pot principle. For example, the doors have marginal sleeves 13 which telescope rods 14 secured to the cabinet. The sleeve end opposed to the rod is blind except for an orifice or bleeder 15. Hence, under the air cushion thus provided the doors when released will gravitate slowly and easily to open position.

A hood 16, of upwardly converging side and end walls, is fitted onto the upper edges of the side walls 1 and 2, and is designed to carry locking means to secure the doors in closed relation. In addition to the usual top or display light, an electric lamp 17 is mounted in the extreme upper portion of the hood, so that the latter acts as a reflector to flood the head room with light.

The locking means includes rods 18 ranging longitudinally of the hood and mounted for rocking movement. They carry latches 19, adapted to engage the upper marginal lips or flanges 20 of the doors to secure the latter in closed position. The rods 18 have radial arms 21, connected by rods 22 to angularly directed arms 23 of pivotally mounted levers 24 in one of the side walls. The levers 24 have terminal eyes 25, and a single padlock is sufficient to lock the system. The rods 18 are normally held in latching position by a suitable spring 26, and the arms 24 need simply be operated to release the door latching mechanism.

Evidently separating movement of levers 24 will shift the latches 19, release the doors, and permit the latter to slowly gravitate to open position without further attention. As before stated, the latch carrying rods 18 are spring influenced towards locking position of the latches, and the connection with the levers 24 is such that the latches can be moved independently of the levers to permit a latching operation of the doors.

Independent or individual tanks 27 and their pump connections are arranged in the cabinet, supported at their lower ends on the frame elements. To secure the pumps in compact unit relation, and also to cause the upper frame cross bars 7 of the frames to interlock with the tanks opposed or duplicate set-screws 28, 29 are provided. Under strain of the set-screws 28, 29, the side bars 7 are held rigidly to insure that the curved edges 8 of such bars to overlie the edges of the tanks, and secure the latter in place. On loosening the set screws, the bars 7 may be forced outwardly to a degree sufficient to release the tanks.

The improved cabinet thus supports a plurality of tanks with their pump connections, the tanks being, however, independently removable, when necessary, while being rigidly held together and within the cabinet under the described securing means. The doors are mounted so that when opening they are simply released and permitted to gravitate

slowly to their open position, thereby obviating the necessity for directly manipulating or handling the doors for the opening operation. The doors present their full surface area in unobstructed view at all times to increase their value as advertising panels. The cabinet is open at both front and rear, permitting access from either point, and permitting a full view of the interior of the cabinet from either point. The top serves to interlock all movable parts, and at the same time provides a means whereby the pumps may be subjected to a flood light for convenience in night use and to provide an attractive display. A single locking means, accessible from the exterior, serves as a complete lock for all parts, and after being released, may be immediately relocked without interfering with the capability of the locking of the doors at any subsequent time. This provides an advantage in avoiding the possibility of overlooking the final locking after closing the doors.

Having described my invention, I claim—

1. A cabinet formed in its lower portion for the reception of independent tanks, doors closing the upper portion of the cabinet above the tanks, guiding elements on the edges of the doors formed as cylinders with closed upper ends having relief openings, and guide rods on the cabinet fitting said cylinders.

2. A cabinet of skeleton form having end walls, a frame for supporting a battery of tanks, said frame being arranged in the lower portion of the cabinet and including upper bars having their marginal edges in register with the upper edges of the tanks, and means for straining such bars to cause their upper edges to engage and hold the tanks.

3. A cabinet formed in the lower portion for the reception of independent tanks, doors closing the upper portion of the cabinet above the tanks, a top carried by the cabinet, means carried by the top for locking the doors in closed relation, operative means accessible from the exterior of the cabinet for actuating the locking means, said operative means being designed for independent locking, the locking means functioning independently of the locked condition of the operative means.

In testimony whereof I affix my signature.
ARTHUR E. DAVENPORT.
